UNITED STATES PATENT OFFICE.

NICHOLAS RATCHFORD, OF GREENVILLE, OHIO.

WIRE-COMPENSATOR AND RAILWAY-SIGNAL.

SPECIFICATION forming part of Letters Patent No. 634,273, dated October 3, 1899.

Application filed December 10, 1897. Serial No. 661,447. (No model.)

To all whom it may concern:

Be it known that I, NICHOLAS RATCHFORD, a citizen of the United States, residing at Greenville, in the county of Darke and State 5 of Ohio, have invented a certain new and useful Improvement in Wire-Compensators and Railway-Signals, of which the following is a specification.

My invention relates to the improvement 10 of wire-compensators of that class which are adapted to be used in conjunction with railway-signal-operating wires, and has particular relation to the improvement of the mechanism set forth in my former Letters Patent, 15 No. 535,921, dated March 19, 1895.

The objects of my present invention are to simplify the construction of the device shown in said former patent, to provide improved means for automatically throwing the target- 20 signal to the danger position in case an operating-wire should become broken, and to produce other improvements in details of construction and arrangement of parts, which will be more fully pointed out hereinafter. 25 These objects I accomplish in the manner illustrated in the accompanying drawings, in which—

Figure 1 is a side elevation of my improved compensator. Fig. 2 is a plan view of the 30 same. Fig. 3 is a side elevation of one of the compensator-sections, showing the same removed from its supporting-framework. Fig. 4 is a side elevation of one of the compensator-sections, showing the arms thereof dis- 35 engaged from the adjusting or draft block. Fig. 5 is a view in elevation of the forward end of a compensator. Fig. 6 is a sectional view on line xx of Fig. 2. Fig. 7 is a detail view in perspective of one of the guide and 40 bar connecting blocks which I employ as hereinafter described. Fig. 8 is a detail view in perspective of one of the draft-blocks. Fig. 9 is a similar perspective view of one of the forward guides, showing a portion of one 45 of the compensator-section bars connected therewith. Fig. 10 is a view in elevation of a semaphore or railway-signal, and Fig. 11 is a detail view in elevation of a coupling-bar which I employ in connecting one of the 50 compensator-wires with the signal-operating lever.

Similar numerals refer to similar parts throughout the several views.

In carrying out my invention I may employ one or more compensator-sections, which 55 are supported and arranged as hereinafter described.

Although the sections forming my improved compensator are shown and described herein as supported horizontally, it will be obvious 60 that the same may be utilized in a vertical position when desired. Each of the compensator-sections consists of two normally parallel bars 1, these bars being rigidly connected at one end of the sections by means of an 65 intervening block 2. This block 2 is provided on its front and rear face with projecting eye-lugs 3, and on the outer and inner faces of each of the blocks 2 I form guide-lugs 4, each of these guide-lugs being 70 provided near its outer end with an angular recess, (indicated at 5,) which results in the production of a short tongue extension 6 on each of said lugs. In their rear halves the upper 75 surface of the lower bar and the under surface of the upper bar 1 are provided with inwardly projecting and inclined teeth 1^a. The rear end of each of the bars 1 is, as shown more clearly in Figs. 3, 4, and 9 of the drawings, secured to the cross-bar of an H-shaped 80 guide-frame 7, the parallel vertical arms of each of these frames 7 having formed on their upper and lower ends outwardly-projecting guide and bearing lugs 8, which are tooth-shaped or triangular in cross-section. 85 Between the toothed portions of the bars 1 I provide an adjusting or draft block 9, two opposite sides of which are provided with teeth which, as shown in the drawings, are adapted to engage with the teeth 1^a of the bars 1. 90 This draft-block is provided on its front and rear sides with projecting eye-lugs 10 and on its outer and inner faces with parallel guide and bearing lugs 11, said lugs 11 being provided with short tongue extensions (indicated 95 at 12.)

With one of the eye-lugs 10 is connected, as shown more clearly in Figs. 3 and 4 of the drawings, one end of a coiled spring 13, the remaining end of the latter being connected 100 with an eye-lug 3 of the block 2. With the rear draft-block lug 10 is connected either

directly or through the medium of a short chain-section, if desired, one end of one of the signal-operating wires 14, the latter extending outwardly between the disconnected 5 ends of the bars 1 and being connected with the usual or desirable form of operating-lever. (Not herein shown.)

A compensator-section constructed as hereinbefore described is adapted to be movably 10 supported within a framework which is formed substantially as follows: From a suitable base 15 rise oppositely-located rear frame-standards 16, front frame-standards 17, and intermediate standards 18, the upper ends of 15 each pair of these standards being connected by a transverse bolt 19, each of which is surrounded between the standards by a sleeve or pipe section 20. Secured to the inner sides of the standards 16, 17, and 18 are oppositely- 20 located horizontal frame-bars 21 and 22, the upper or outer frame-bars 21 having their rear end portions inclined upwardly and outwardly, as indicated at 23, while the lower frame-bars 22 have their rear end portions inclined downwardly, as indicated at 24. Compensator-supporting frames formed as 25 above described are adapted as shown in Figs. 1 and 2 of the drawings, to be arranged side by side, and one of the compensator-sections, formed as hereinbefore described and 30 shown more clearly in Figs. 3 and 4, is, as indicated by other figures, adapted to be movably supported in each of said frames. In thus supporting one of the compensator-sections in one of said frames the projecting 35 tongues 6 of the block 2 are adapted to project between the upper and lower frame-bars 21 and 22, while the projecting guide-lugs 8 of the H-shaped frames 7 embrace the upper 40 and lower sides of said horizontal frame-bars.

With the forward eye-lugs 3 of the blocks 2 are connected the rear ends of signal-operating wires, which in this case are shown at 25 and 26.

45 27 represents a vertical semaphore or signal post, on the upper portion of which is fulcrumed the usual signal-arm 28, one end of said arm carrying at right angles therewith a danger-blade 29 and the remaining arm end 50 carrying a suitable light-support 30.

At a point below the signal-arm 28 I cause to be fulcrumed to the post 27 an operating or lever arm 31, the latter being provided in the usual manner near one end with an adjustable weight 32. On one side of the center of its length the lever-arm 31 has fulcrumed thereto one end of a connecting-rod 33, the remaining end of which is fulcrumed to the signal-arm 28. Depending from the 55 lever arm or bar 31 on opposite sides of its fulcrum-point are keepers or guide-lugs 34, which form a support for a sliding rod 35, which passes loosely therethrough. At a 60 point on the lever-arm 31 near one of its ends 65 is fulcrumed a wire-supporting trigger 36, which has substantially the bell-crank form

shown and which has a notch in its upper side. At a point on the lever 31 on the opposite side of its fulcrum-point from that on which the trigger 36 is located I fulcrum a 70 second bell-crank 37. The longer and normally upper arm of this bell-crank 37 is jointedly connected at 38 with the upper end of a short downwardly-extending bar 39. With the lower end of this bar 39 is suitably 75 connected the upper end of the signal-operating wire 25, while with the notch of the longer arm of the bell-crank 36 is engaged the upper end of a coupling-bar 25^a, the latter having a mortise 25^b in its upper portion to 80 receive said bell-crank arm, as shown. With this coupler is connected the upper end of the operating-wire 26. These wires 25 and 26 run from the compensator-sections to said points of connection. It is obvious that in 85 order to retain the loop engagement of the wire 26 with the longer arm of the bell-crank 36, said bell-crank arm must be retained in a position parallel with the lever-arm 31 and adjacent to the latter, while the coupler-bar 90 25^a of the wire 25, which engages with said bell-crank arm, projects in a notch 40 in the under side of the lever-arm 31. In this position the longer arm of said bell-crank lever 36 also has a bearing against the under side 95 of a suitable lug 41, which projects from the outer end portion of the lever-arm 31. The bell-crank 36 is normally retained in the last-described position through contact of its shorter arm with one end of the sliding rod 100 35, the remaining end of said sliding rod being in contact with the shorter arm of the bell-crank 37 and operating to retain the longer arm of the latter in the elevated position shown in Fig. 10.

105 In order to more clearly describe the operation of my device, I will distinguish the two compensator-sections shown by referring to the same as the "outer" and "inner" sections. Assuming that a pull is exerted on that wire 110 14 which connects with the inner compensator-section and with which section is also connected the wire 26, it is obvious that said inner section and the toothed bars 1 which are engaged therewith will be drawn rearwardly until the guide-lugs 8 by engagement with the inclined upper and lower sides of the frame-bars 21 and 22 will have separated said bars 1 until the teeth thereof are out of engagement with the draft-block of the corresponding section, as indicated more clearly 115 in Figs. 1 and 4 of the drawings. It is evident that the pull on the wire 26 which will result from the movement of the inner compensator-section has resulted in the weighted end of the lever-arm 31 being drawn upward to the position shown in the drawings, and this upward movement of said arm end has resulted in the signal being turned with its danger-blade 29 downward to the position 120 shown in Fig. 10. Through the above-described upward pull of one end of the lever- 125 130

arm 31 the wire 25 is drawn upward, resulting in the outer compensator-section with which said wire is engaged being drawn toward the front end of its supporting-frame, 5 as indicated in Figs. 1 and 2. It is evident that while the draft-block of the inner section is, in the manner above described, disengaged from the teeth of the bars 1 the spring 13 may operate to take up any slack 10 of the wires or admit of the extension thereof.

When the pull is exerted on the wire 14 of the outer compensator-section in order to reverse the position of the signal, it is evident that said pull will only exert an influence on 15 the spring 13 of the inner section until the guide-lugs 8 of said inner section have traveled on to the straight portion of the frame-bars, at which time the teeth of the draft-block of said inner section will engage with 20 the teeth of the side bars 1.

During the sliding movements of the compensator-sections above described attention is called to the fact that the projecting tongues 6 and 12 of the blocks 2 and 9 will slide between 25 the upper and lower frame-bars 21 and 22 of the framework, the space between said bars providing a guideway for said tongues, thus obviating the necessity of employing the slotted guideways for the reception of the 30 guide-pins of my said former patent. It will also be observed that instead of providing a projecting guide-pin at the end of each of the toothed bars I have provided the lugs 8, which embrace opposite sides of the longitudinal 35 frame-pieces and provide a positive means for directing the movement of the said bars.

In case one of the compensator-wires—for instance, the wire 25—should by accident or otherwise become broken or separated it will 40 be observed that the bell-crank 37 will be free to swing on its fulcrum-point and that the shorter arm of said bell-crank 37 will no longer offer resistance to the rod 35. The rod 35 being thus free to move in its bearings, 45 it is obvious that the longer arm of the bell-crank 36 will drop downward until the coupler-bar 25^a and the wire 26 are released therefrom, thus allowing the weighted end of the lever-arm to drop downward and causing the 50 blade 29 to swing upward and outward to the danger position.

In case of a breakage of the wire 26 it is obvious that the tension on the wire 25, in conjunction with the blade 22, must also result

in said blade 29 swinging to the danger position. 55

It will thus be seen that simple, reliable, and effective means are provided for throwing the signal to the danger position in case either of the operating-wires should become broken 60 or disconnected.

From the construction and operation herein set forth it will be seen that not only are simple, reliable, and effective means provided for compensating for the contraction and expansion of the wires, but that improved and effective means are provided for guarding against accident by throwing the signal to the danger position in case of breakage or similar accident to the lever-operating wires. 70

Having now fully described my invention, what I claim, and desire to secure by Letters Patent, is—

1. In a wire-compensator and railway-signal, the combination with a compensator-frame, sliding compensator-sections arranged therein wire connections between said compensator-sections and operating mechanism, and signal-wires 25 and 26 also connected with said compensator-sections, of a signal-post, a 75 fulcrumed semaphore thereon, a fulcrumed lever-bar 31 on said post, a rod jointedly connecting said bar and semaphore a weight on one end of said bar, bell-cranks 37 and 36 fulcrumed on said lever-bar on opposite sides of 80 the fulcrum-point of the latter, a sliding rod 35 supported from said lever-bar and having its ends in contact with the downwardly-extending arms of said bell-cranks, said wires 26 having a loop engagement with one arm of 85 the bell-crank 36 and said arm 25 having an engagement with one arm of the bell-crank 37, substantially as and for the purpose specified. 90

2. The combination with a fulcrumed bar 95 31, of wire-holding bell-cranks fulcrumed to said bar on opposite sides of the fulcrum-point of the latter, normally-taut wires 25 and 26 connected with and supported by said bell-cranks and means for so supporting said 100 bell-cranks as to result in case one of the wires is broken, in the release of the wire, substantially as and for the purpose specified,

NICHOLAS RATCHFORD.

In presence of—

C. C. SHEPHERD,
A. L. PHELPS.
